UNITED STATES PATENT OFFICE.

HARVEY L. HARRIS, OF ELYRIA, OHIO, ASSIGNOR, BY MESNE ASSIGNMENTS, TO THE GARFORD MANUFACTURING COMPANY, OF ELYRIA, OHIO, A CORPORATION OF OHIO.

TELEPHONE SYSTEM.

1,161,048.

Specification of Letters Patent. Patented Nov. 23, 1915.

Application filed August 2, 1911. Serial No. 641,903.

To all whom it may concern:

Be it known that I, HARVEY L. HARRIS, a citizen of the United States, residing at Elyria, in the county of Lorain and State of Ohio, have invented certain new and useful Improvements in Telephone Systems; and I do hereby declare the following to be a full, clear, and exact description of my invention, such as will enable others skilled 10 in the art to which it appertains to make and use the same.

This invention relates to telephone systems, and more particularly to what is known as private branch exchange systems, 15 though I contemplate employing my invention upon other exchange systems where it may be conveniently used.

At times the service of the operator at a telephone exchange or at a section of a 20 telephone exchange may be dispensed with and the calls received at that board or that part of the board attended to by some other person, such as another operator or an attendant about the office. This happens at 25 certain hours during the day or night at nearly every private branch exchange in service in this country. For example, in hotels during the night hours, the operator is off duty and the hotel clerk or some 30 other attendant must answer the calls. As the switchboard may be located some distance from the desk or other place where the clerk or attendant is normally employed, it will save considerable time and trouble if 35 these calls can be answered from the telephone of such attendant.

One of the objects of my invention is to provide a system, such that the attendant or another operator may answer the calls from 40 his own telephone without having to go to the board and there answer the call.

Other objects of my invention and the invention itself, will be best understood by referring to the following description and 45 the drawing accompanying the same, which when taken together, illustrate specific embodiments of the invention, while the scope of the invention itself, will be more particularly pointed out in the appended claims.

Figure 1 is a diagram of one form of my 50 invention. Fig. 2 shows a modification.

Referring now to the drawing and to the embodiment of my invention shown therein, at A I show a central station here illus-

trated as a private branch exchange system 55 and at B and C substation circuits. Any number of substations may be connected to the private branch exchange system, I having shown but two here, as two are sufficient to illustrate my invention, the objects and 60 the operation thereof. The station B is connected by conductors 1 and 2 to a jack J at the exchange and the substation C by conductors 3 and 4 to a jack J' at the exchange. The springs 5 and 6 of the jacks normally 65 rest against contacts 7 and 8 which may be connected by conductors 8' and 9 to the common conductors 10 and 11. These conductors are normally grounded through the contacts 12-13-14-15 of a relay R. The 70 circuit of the relay R is controlled by a relay R₁, which is connected to a plug P by conductors 16 and 17. The line relays are shown at R₂ and R₂'. The line lamps are shown at L and L'.

Q is an alarm bell controlled by a relay R₃, which is in turn controlled by the line relay. A source of current is shown at X.

The objects of my invention and the apparatus employed in the specific embodiment illustrated and its functions will be best understood from a description of the operation, which is as follows: When the operator at the exchange or at a section of the exchange, desires to leave her position, 85 the plug P is inserted into the jack of one of the subscribers' lines, which happens to be a line of the party who is to attend to the calls coming in at the board or at that section of the board during the absence of 90 the operator. The tip 20 connected with the strand 17, engages the jack spring 5, opening the switch 5-7 and the sleeve 21 of the strand 16, engages spring 6 of the jack, opening the switch 6-8 and cutting 95 the line 1-2, (which for the sake of clearness, we will call the attendant's line), off from the common conductors 10 and 11.

Now should a call come in, for example, from the party at the station C, the receiver hook 22 at the station rising when the receiver is removed therefrom, engages the contact 23, completing the following circuit: 23-3-5-7-8'-10-12-13 to ground at G, through the ground to the 105 grounded pole of battery X, through battery X-conductor 24-conductor 25-relay R₂'-8-6-4, transmitter T to the contact

22, thus completing the circuit. The relay R_2' is energized, pulling up its armature 26, closing the switch 26-27 and completing the circuit through the lamp L' and relay R_3 as follows: ground G_2 -15-14-9-26-27-6-8-28- L' - R_3 -the conductor 29-armature 30-contact 31-24-battery X to ground at G_1 , thus completing a circuit through these members. The lamp 10 L' is actuated while the relay R_3 is energized, pulling up its armature 31' and closing a switch 31'-32, which completes a circuit from the bell Q as follows: ground G_4 - Q -conductor 35-32-31'-24- X to ground at G_1 , operating the bell. It will be apparent that any suitable indicator may be employed in the place of the lamp or the bell and such indicator may be located at any convenient position, such for example, 20 at the position of another operator, at the clerk's desk or in another apartment. The attention of the attendant being attracted by the indicator, the receiver V at substation B is taken from the hook 40, which 25 rising engages the contact 41, completing the following circuit through the relay R_1 : grounded pole of battery X -winding 42 of the relay R_1 -17-20-5-1-41-40-transmitter T_1 -2-6-21-16 to the other winding 43 and the other pole of the battery X . The relay R_1 is energized, attracting its armature 44 and closing the switch 44-45. This completes a circuit through the relay R as follows: G_1 - X -46-44-45- R 30 to ground at G_5 . The relay R is energized, pulling up its armatures 12 and 14, cutting the conductors 10 and 11 off from ground, connecting them through the armatures 12 and 14 with the contacts 50 and 51 and the conductors 16 and 17 and completing the circuit between the substation B and C as follows: from the switch hook contact 41 at substation B , through 1-5-20-17-51-14-11-9-26-27-4- T -22-23-45 3-5-7-8'-10-12-50-16-21-6-2- T_1 -40, completing the circuit. Current is supplied to this circuit from the battery X through the winding 42 and 43, the battery being thus bridged across the talking line. Conversation is carried on over this circuit. When terminated, the receiver V is restored to the switch-hook 40 which opens the circuit at 40-41. This 40 interrupts the circuit of the relay R_1 previously traced through this switch. The relay R_1 is accordingly deenergized, which breaks the circuit through the relay R at 44-45, so that the system is restored to normal. When the relay R is energized, the indicators which receive current through the switch 14-15 are retired.

In the form shown in Fig. 2, the attendant's substation is illustrated at B' . Here the line 1'-2' is connected to the conductors 16 and 17 by a switch operated by a key or

some other suitable means which is substituted for the plug P . This switch is shown at W .

While I have shown these particular forms of my invention, I do not wish to be limited thereto, as it will be obvious to those skilled in the art that numerous and extensive departures from the forms and details of the apparatus shown therein, may be made without departing from the spirit of my invention, these forms being shown solely for the purpose of clearly illustrating specific embodiments of the invention.

Having thus described and illustrated my invention, what I desire to claim is:

1. In a telephone exchange system, the combination of a plurality of telephone lines, substations connected upon said lines, a central station and means whereby the substations may call the central station, a plurality of conductors common to said telephone lines, connective means, including a plug and jack switch, at the central office to designate one of said substations as an attendant station, a relay device associated with said connective means, a relay device associated with each of the said telephone lines, means to establish a circuit between the attendant station and a calling station, said means being automatically and jointly controlled by the first-named relay device and the relay device associated with the calling line.

2. In a telephone system, a plurality of telephone lines, substations on said lines, a central office to which the lines lead, means at the central office to connect the lines together, a selective circuit at the central office under the control of the operators to select one of the telephone lines as an attendant line, a relay in said selective circuit, relay mechanism associated with each of the telephone lines, a plurality of common conductors, each of said relay mechanisms adapted to connect its associated telephone line to the common conductors to establish a conversational circuit between the line with which it is associated and the attendant station, said relay device and the relay mechanism of the calling line adapted to jointly disestablish such conversational circuit.

3. In a telephone exchange switchboard, connection terminals associated therewith, telephone lines containing sub-stations, said telephone lines being connected to said connection terminals, circuit conductors common to the telephone lines, a relay device associated with each of the said connection terminals adapted when operated by the connected sub-station apparatus to connect its associated telephone line to said circuit conductors, selective means under the control of the operator at the switchboard for

- selecting one of the telephone lines, a relay device adapted to be operated by the apparatus at the sub-station of the selected telephone line for connecting said selective means 5 to said circuit conductors, said last named relay device being thereafter under the control of the interconnected sub-stations to disconnect said sub-stations.
4. In a telephone system, the combination 10 of a plurality of telephone lines, sub-stations thereat, a switch-hook at each of the sub-stations, switchboard jacks at a central office for said telephone lines, conductors common to said telephone lines, a relay device operated by the switch-hook at the sub-station for connecting its associated telephone line with 15 said conductors, a second relay device associated with the telephone lines for operating an alarm signal, a relay associated with said 20 trunk circuit, a selective circuit including a plug switch, said plug switch adapted to be inserted in one of the switchboard jacks to select an attendant station, an electromagnet associated with said selective circuit to operate 25 said relay when the switch-hook at the attendant station is operated, to connect said attendant station to said trunk circuit and to disconnect said alarm signal.
5. In a telephone system, a main station, 30 a plurality of substations, telephone lines leading from the substations to the main station, a line relay and a line signal controlled thereby associated with each telephone line, a plurality of common conductors, a circuit under the control of the 35 line relay for connecting its associate telephone line with the common conductors, a source of current, other conductors connected with the source of current, switching 40 mechanism associated with said other conductors, including a manual switch and a relay device, said manual switch adapted to connect one of said substations designated 45 an attendant station with said other conductors, said relay device being controlled by said attendant substation set and adapted when operated to connect said common conductors with said other conductor.
6. In a telephone system, the combination 50 of a plurality of substations, an exchange station, telephone lines connecting said substations with said exchange station, means at said exchange station normally connecting said lines together, an attendant's substation normally disconnected from said 55 means, means under control of said attendant for connecting the attendant substation to said first named means, said last named means being partially under the control of a calling subscriber. 60
7. In a telephone system, the combination 65 of a plurality of substations, an exchange station, telephone lines connecting said substations and said exchange station, said substation lines being normally connected together at the exchange station, an attendant's station, a telephone line connecting said attendant's station to said central station, said attendant's line being normally disconnected from said substation lines and 70 means controlled by the apparatus at the attendant's station for connecting said attendant's line to a calling line, said means being thereafter jointly controlled by the attendant at the substation and a calling subscriber for disconnecting the aforesaid lines. 75
8. In a telephone system, the combination 80 of a plurality of substations, an exchange station, a plurality of telephone lines connecting said exchange station to said substations, an attendant's substation, an attendant's line connecting said attendant's substation to said exchange station, said substation lines being normally connected together, means to disconnect one of said stations from such common connection and means to connect such disconnected substation in circuit with a source of current and a calling substation. 85

In testimony whereof, I affix my signature 90
in the presence of two witnesses.

HARVEY L. HARRIS.
